[57] **CLAIM**

The ornamental design for a tote bag, as shown and described.

DESCRIPTION

FIG. 1 is a perspective view of a first embodiment of a tote bag showing the design of my invention;
FIG. 2 is a top plan view of FIG. 1;
FIG. 3 is a bottom plan view of FIG. 1;
FIG. 4 is a front elevational view of FIG. 1;
FIG. 5 is a rear elevational view of FIG. 1;
FIG. 6 is a left side elevational view of FIG. 1;
FIG. 7 is a right side elevational view of FIG. 1;
FIG. 8 is a perspective view of FIG. 1 with the attached body cover thereof shown in an open position;
FIG. 9 is a perspective view of a second embodiment of a tote bag showing the design of my invention;
FIG. 10 is a top plan view of FIG. 9;
FIG. 11 is a front elevational view of FIG. 9;
FIG. 12 is a bottom plan view of FIG. 9; and,
FIG. 13 is a perspective view of FIG. 9 with the attached body cover thereof shown in an open position.
The broken lines are for illustrative purposes only and do not form part of the claimed design.
